UNITED STATES PATENT OFFICE.

CHARLES J. KINTNER, OF NEW YORK, N. Y.

RAILWAY SIGNAL AND SAFETY APPLIANCE.

No. 869,970.

Specification of Letters Patent.

Patented Nov. 5, 1907.

Application filed August 10, 1905. Serial No. 273,671. Renewed January 18, 1907. Serial No. 352,962.

To all whom it may concern:

Be it known that I, CHARLES J. KINTNER, a citizen of the United States, residing in New York, borough of Manhattan, county and State of New York, have made a new and useful Invention in Railway Signals and Safety Appliances, of which the following is a specification.

My invention is directed to improvements in railway signals controlled by a constantly acting force, as gravity in one direction, and an applied source of energy, as an electric motor, in the reverse direction, for setting them so as to indicate the condition of the block sections, or other features of warning to which they relate, and in such manner that when released the constantly acting force will set them to indicate a definite condition, as danger.

It also relates to safety appliances for automatically effecting the stoppage of a car or train in the event of danger thereto, due either to an abnormal track condition or to the failure of the controlling devices of either the signals or the stop devices, and to these ends it has for its objects, first, to provide means for setting a signal in any one of two or more definite positions so as to indicate one or more conditions by causing the controlling force to be applied in reverse directions and in such manner that when the signal is left set in either of the aforesaid positions the constantly acting force, as gravity, tends always to move it to a definite position indicating danger. Second, to combine such a signal with a main track, a side track and a rail switch and in such manner that when the switch is in one position and the signal held against the force of gravity it is exposed to view pointing in one direction and against the constantly acting force, as gravity, and when the switch is moved in a reverse direction the signal is likewise moved by the applied force into a diametrically opposite position and held as before against the constantly acting force, as gravity, the signal giving three indications; (1) main track rails in alinement; (2) side track rails in alinement; (3) danger, the arrangement being such that always when the constantly acting force of gravity is permitted to act to move the signal it goes to a definite position, as danger. Third, to provide means for controlling the movement of a signal, as a semaphore, through the agency of a single electric motor adapted to move the same in either direction against the force of gravity and to lock it when so moved to the limit in either direction with the motor out of circuit, combining there-

with means for interrupting the motor circuit should the locking means fail to act. Fourth, to combine with a main track a side track and a switch for the track rails thereof, a switch signal operated by an electric motor, and provided with means whereby when the switch-rails are moved in opposite directions the rotary armature of the operating motor of the signal

is caused to rotate in different directions. Fifth, to combine with a main track and a side track, a switch for moving the switch rails, a main source of electrical energy, a rotary electric motor and a signal operated thereby and an independent source of electrical energy for locking the signal in different positions against the force of gravity; together with means operatively connected with the switch for causing the armature of the motor to rotate in different directions. Sixth, to provide a train control or stop device carried by a car or train and adapted to control either the source of power thereof, or the brakes, or both, and to combine therewith a power impelled semaphore so constructed and arranged that when the semaphore stands in a definite position the train stopping device will not be actuated and when it stands in either of two other positions said train stopping device will always be actuated. Seventh, to provide a stop device beside the roadway for automatically effecting the stoppage of a train when abnormal track conditions occur, or when the controlling force which effects the release of such stop device is interrupted or disturbed, said stop device being of a double or duplex nature and so constructed and arranged that (a) when the main track is clear it is out of operative relation; (b) when the side track is in alinement for side tracking a train it is in operative relation for stopping the train; (c) when the controlling source of energy fails it is also in operative relation for stopping a train, all trains or cars passing over the route being provided with automatic train controlling apparatus adapted to be actuated by said stop device.

In prior applications for patents filed by me in the U. S. Patent Office I have disclosed railway signals in the nature of semaphores operated by electric motors in one direction only against a constantly acting force, as gravity, and controlled by the application of electrical energy, and I have shown, described and claimed train stopping devices carried by a car or train adapted to disconnect the source of power and to apply the brakes through the agency of the semaphores themselves when released or set in definite positions, as danger.

In all of the before-mentioned applications, however, the semaphores have been rotated always in the same direction and set or locked against the force of gravity, said semaphores being capable of indicating two positions only; namely, safety, or danger; or safety or caution, where distant signals are used.

The present invention contemplates the application of rotary electric motors to the movement of semaphore signals in different directions and in such manner as to give different individual indications always leaving the semaphore or signal when set or locked under the influence of a constantly acting force, as gravity, and I effect this novel result through the agency of pole

changing means whereby when it is desired to have the signal set in either one of two definite positions the armature of the motor is caused to rotate in the proper direction by causing the controlling current to flow in such direction therethrough as to effect the result, the arrangement being such that when the semaphore has reached its indicating position it is locked with the motor cut out of circuit.

The present invention also contemplates the use of 10 a double or duplex stop device operated and controlled by two sources of energy, as gravity and electricity, and adapted for use particularly in connection with side tracks in railway systems, said stop device being so constructed that (a) when the main track rails are in 15 alinement it is normally held out of operative relation with a train controlling device carried by a car or train; (b) when the main track rails are in alinement with the side track rails it is in operative relation with the train controlling device carried by the car or train; (c) when 20 the controlling source of energy fails or is interrupted it is also in operative relation with the train control device carried by the car or train.

For a full and clear understanding of my invention, such as will enable others skilled in the art to construct 25 and use the same, reference is had to the accompanying drawings, in which,

Figure 1 is a diagrammatic view illustrating an electric motor having its armature operatively connected to a semaphore or signal and to the operating circuit of 30 a dynamo electric machine; a pair of main track rails, a pair of side track rails, a rail switch and a pole changer connected thereto for varying the direction of the current flow to the armature of the motor when the switch is closed being also shown, the signal being shown as 35 locked in a definite position through the agency of a locking device controlled by a source of electrical energy wholly independent of and disconnected from the main source of current supply which drives the motor. Fig. 2 is a transverse section taken through the road- 40 bed of a railway and the signal box inclosing one of my novel signals, a car being shown in end view and train controlling devices carried thereby, the signal box being supported by a semaphore post beside the track.

Referring now to the drawings in detail, and first to 45 Fig. 1, 1, 1, 1, 1 represent the rails of the main track, 2, 2, the rails of a side track, and 3, 3, a pair of switch rails shown in alinement with the main track rails and connected by a switch rod 4 with a switch-lever 5 pivoted at 6 and provided with an operating handle 7, said 50 parts 4 and 5 constituting means for moving the switch rails 3, 3, and termed by me throughout the specification and the claims a rail-switch. 8 is the movable part of a pole changing device carried by the switch-lever 5, and 9, 10 are movable contact plates carried 55 at the other end of the switch lever 5, the plate 10 being insulated from said lever. 11, 12, 11, 12 are stationary contacts located on opposite sides of said movable contact plates. 13, 14 are pole changing contact springs located in the path of the movable part 8 of the pole 60 changer. 15 is the stationary part of the pole changer and 16, 16 are branch conductors running from the pole changing contact springs 13, 14 to and through the armature coils of an electric motor 17. 18 is a semaphore attached at one end to a circular disk and both secured 65 to a shaft carrying a gear-wheel which meshes with a

pinion on the armature shaft. 19 is a stop arm or device supported by the same disk which supports the semaphore 18 and lying in a plane 90° from a plane passing through said semaphore. 20 is a locking conducting armature lever and 21 a movable contact plate 70 carried at the free end thereof and adapted to contact with a fixed contact plate 22 in the motor conductor 16. 23, 24 are pivoted switches located in series relation with the conductor 16 and in the path of a pin 25 carried at the free end of the semaphore 18. 26 is a 75 locking electromagnet included in a circuit 27 with a local battery 28 or other source of electrical energy wholly independent of or disconnected from the main source of energy which operates the motor.

The semaphore arm 18 and the stop arm 19 together 80 with their supporting shaft constitute a double or duplex stop device operated by a single electromotive device and controlled by a single electro-magnetic locking device, and the structural arrangement is such that with a single electromotive device and a single locking 85 device I am enabled to automatically effect the stoppage of a train for three abnormal conditions, two of the same being track conditions and the third a failure of the source of energy which locks or holds the stop device at safety.

D is a dynamo electric machine or main source of electrical energy for operating the motor 17 and m, m, are current mains connected thereto; w, w, being branch conductors running from the current mains to the stationary contacts 11, 11, 15, and m¹, m¹ a shunt 95 circuit connecting the field magnet coils of the motor 17 directly in circuit with the current mains m, m.

Referring now to Fig. 2, C represents a car the wheels of which are standing upon the track rails 1, 1, s, s, represent the operating arms of two train controlling 100 devices located on opposite sides of the car, the same being substantially like similar devices disclosed in a prior application filed by me in the U. S. Patent Office on the 9th day of May, 1905, Serial No. 259,625, and adapted to control the application of power and of the 105 brakes when the car is traveling in either direction. S represents a semaphore post beside the track and A a semaphore box completely protecting the operative parts of the apparatus disclosed in Fig. 1 and shown therein as inclosed in broken lines.

R, R represent two red colored glass lenses and W a white glass lens all carried by the same disk which supports the semaphore 18, the two lenses R, R being 90° apart and the lens W 90° from one of the before-mentioned lenses and 180° from the other, the lamp being 115 shown in this figure of the drawings behind the white lens W, and the semaphore 18 in full lines at safety indicating a main track connection; and in dotted lines indicating a side track connection.

Suppose the car C to be traveling in the diagrammatic view Fig. 1 from right to left and the track rail and circuit relations as therein disclosed; that is to say, with the switch rails 3, 3, in alinement with the main track rails 1, 1. Under this condition of affairs current flows from the positive pole of the dynamo electric 120 machine D by the plus current main m to and through the field magnet coils of the motor 17 by shunt circuit m¹ to the negative current main m, and a branch thereof tends to flow through the current main m, branch conductor w, upper stationary contact 11, movable 125

90

110

115

120

125

130

- contact plate 9, switch lever 5, movable part 8 of the pole changer, pole changing contact spring 13, conductor 16, through the armature of the motor 17, armature lever 20 and movable contact plate 21 at the free end thereof, where it is interrupted, the semaphore being locked in the position shown in both figures of the drawings against the force of gravity due to its own weight, by a detent on the armature of the lever 20, extending into one of the two locking notches as shown: 5
- 10 consequently, indication is given to the motorman on the car C, Fig. 2, by reason of the semaphore 18 extending transverse the track and in a direction toward the same, that the switch rails 3, 3, are in alinement with the main track rails 1, 1 and he may proceed. At night 15 the rays from the lamp through the white lens W will give a like indication. Should the switch lever 5 be thrown in a reverse direction the first effect is to break the main circuit of the generator D between the movable contact plate 9 and upper stationary contact 11 and 20 the local circuit 27 of the battery 28 between the movable contact plate 10 and upper stationary contact plate 12, so that the magnet 26 is demagnetized and the armature lever 20 released; consequently, the semaphore 18 falls immediately by its own weight into a vertical 25 position indicating danger and at the same time the movable contact plate 21 closes the motor circuit through the conductor 16 and stationary contact plate 22. As the switch handle 7 is carried forward the movable part 8 of the pole changing device comes into 30 contact with the pole changing contact spring 14 and lifts it out of contact with the stationary contact 15, the main circuit from the generator D, through the armature of the motor, and the local circuit from the battery 28 remaining open until after the spring 14 has 35 been lifted out of contact with the stationary contact 15. Further movement brings the free end of the contact spring 13 into contact with the contact plate 16 and the movable contact plates 9 and 10 into contact with their respective lower contacts 11 and 12. When 40 this occurs the switch rails 3 have been thrown to their limit and the main track rails 1, 1, are now in alinement with the side track rails 2, 2, for side tracking an incoming train. Current now flows from the generator D by the plus current main m, branch conductor w, lower 45 contact plate 11, movable contact plate 9, switch lever 5, movable part 8 of the pole changing device; movable contact spring 14, conductor 16, switches 23—24, stationary contact 22, movable contact plate 21, armature lever 20, through the armature coils of the motor; conductor 16, by way of contact spring 13, stationary contact 15 and conductor w, to the other current main and negative pole of the generator D. Consequently, the motor running in a reverse direction rotates the semaphore 18 into the position shown in dotted lines Fig. 2. 50 At the same time that the working current was closed between the movable contact plate 9 and stationary contact 11 the circuit 27 from the battery 28 and through the electromagnet 26 was closed between the movable contact plate 10 and lower stationary contact 55 plate 12, so that the armature lever 20 was drawn forward; but the detent on the free end of said lever at this time rests upon the cylindrical surface of a disk which is provided with the two locking notches, as shown; so that the motor circuit cannot be interrupted until 60 this disk is rotated through 180°, at which time the locking armature lever 20 is drawn forward and the detent falls into the notch locking the signal in the position shown in dotted lines Fig. 2 and interrupting the motor circuit between the movable and stationary contact plates 21 and 22. 70
- The stop arm or device 19 has now been rotated through 180° from the position shown in full lines, Fig. 2, and into the position shown in dotted lines so that it is in the path of the operating arm s of the train controlling device carried by the car C, and should the train proceed it will be automatically stopped. For like reason should the battery 28 fail, or the circuit thereof be interrupted at any time when the signal is locked in either of the two positions hereinbefore described, the weight of the semaphore 18 will cause 80 it to drop into a vertical position in the path of the aforesaid arm, thus giving indication of the fact that the semaphore is out of order and stopping the train. When the semaphore is in the position shown in full lines the white lens W is in front of the lamp and gives 85 an indication of safety. When said semaphore is in a vertical position the upper red lens R is in front of the lamp giving indication of danger and when in the position shown in dotted lines the second red lens R has been rotated through 180° giving an indication of 90 danger; or, if preferred, this lens may be green giving a special indication of the fact that the switch rails 3, 3 are set for the siding. 95
- Should the battery 28 fail or should the circuit thereof be interrupted in any manner the motor circuit will, of course, be immediately closed, no matter in which position the switch lever 5 may be thrown, so that it becomes necessary to provide means for preventing the motor from rotating the signal continuously, as would be the case should the contact plate 21 be allowed to 100 remain permanently in contact with the stationary contact plate 22. To avoid a possibility of such an occurrence two rotary switches 23, 24 are located in series relation in the branch conductor 16 and in the path of the pin 25, so that should the motor circuit be 105 left closed for any reason, as indicated, no matter in which direction the semaphore may be moved the pin 25 will interrupt the circuit and, consequently, the semaphore will drop by its own weight to danger. Two switches 23, and 24 are preferably used and located 110 as shown for assuring the fact that when the pin 25 strikes either one or the other, dependent upon the direction of rotation, there will be sufficient weight at the end of the semaphore, owing to its angular position at that time, to assure its dropping to a position of 115 danger. In other words, if only one switch were used it would be necessary to locate it at a central position corresponding to the indicated position of the stop-arm or device 19 and it might possibly occur that the semaphore would stop on dead center, the arrangement 120 of switches shown avoiding any possibility of failure for the signal to go to danger when the battery fails or the circuit thereof is interrupted in any way. 125
- I do not limit my invention to all of the especial details of construction disclosed in the accompanying drawing, hereinbefore described and hereinafter claimed, as a number of the features thereof might be departed from and still come within the scope of my claims. To illustrate, although I have shown the novel semaphore and semaphore operating and con- 130

trolling mechanism as applicable to a switch, a main track, and side track rails, many of the features thereof may be utilized in connection with railway signals generally, one of the essential points of novelty of my invention being the feature of controlling a semaphore, or equivalent signal by a source of applied power, as a rotary electric motor, which opposes a constantly acting force, as gravity, in such manner as to permit of the setting of the signal in different positions and maintaining the same locked or held in said different positions against the force of gravity with the motor out of circuit, so that when released it will always assume a definite position indicative of a definite condition, as danger. In other words, I believe it is broadly new with me to rotate a signal in different directions by a single source of energy, as a rotary electric motor, acting against a constantly acting force as gravity, and to maintain said signal in any one of said positions by locking or holding means and in such manner that when released the constantly acting force will always positively so act upon the signal as to give a well defined indication of condition, such as danger, and my claims are generic as to these features.

Although I have shown and described a semaphore as the preferred form of signal for use with my invention, I do not limit myself to such signal, as obviously the same may be utilized with any type thereof, either visible or audible, which may be caused to move by or be actuated through the movement of the rotary armature of an electric motor, and my claims are also generic in this respect. Nor do I limit my invention to its use in connection with railways, as obviously the same may be applied in systems of signaling generally.

A further important feature of my invention lies in locating the contact plates 9 and 10 on the switch lever 5 at a relatively great distance from the pivot point 6, by which arrangement, it will be noted, it is impossible to move the switch lever any material distance and hence the switch rails 3, 3, without displaying the signal 18 at danger, it being absolutely necessary that the switch lever must be moved through its complete phase in either direction to set the signal.

Having thus described my invention what I claim and desire to secure by Letters Patent of the United States is—

1. In a railway system a signal operatively connected to the rotary armature of an electric motor and adapted to hang by its own weight when released in a vertical position; in combination with means for causing said armature to rotate in reverse directions, and means for locking the signal in either one of two definite positions against a constantly acting force, as gravity; together with electromagnetically controlled means for interrupting the motor circuit when the signal is thus locked, substantially as described.

2. In a railway system a signal constructed so as to hang by its own weight when released in a vertical position and operatively controlled by a single source of power adapted to move it in opposite directions against a constantly acting force, as gravity; in combination with means for locking the signal in either of one or more definite positions no more than in opposite directions and additional means for disconnecting the first-named source of power from the signal during the time that it is so locked, substantially as described.

3. In a railway system a signal operatively connected with a single source of power adapted to move it in opposite directions against a constantly acting force, as gravity; in combination with locking means for locking it in

either, of one or more definite positions with the source of power disconnected; together with means for releasing said signal, the arrangement being such that it gives either of two indicated positions of a definite nature when locked and a single definite position indicating danger when released, substantially as described.

4. In a railway system a signal operatively connected with an electromotive device adapted to move the signal in opposite directions against a constantly applied force, as gravity; in combination with a source of electrical energy for actuating said electromotive device and means for varying the direction of movement of the signal through a variation of current effect upon the electromotive device; together with means for locking the signal in a definite position, and additional means for simultaneously disconnecting the source of electrical energy from the electromotive device, whereby the signal remains locked in such definite position with the constantly applied force acting thereon, substantially as described.

5. In a railway system a signal adapted, when released, to hang by its own weight in a vertical position and operatively connected with the rotary armature of a single electric motor; in combination with a source of electrical energy for propelling said motor; a pole changing device for varying the direction of current flow through the motor in such manner as to move the signal in opposite directions, when desired; and means for locking the signal in a definite position against a constantly applied force; together with circuit interrupting means for simultaneously interrupting the current supply to the motor, substantially as described.

6. In a railway system a signal operatively connected with the rotary armature of a single electric motor; a source of electrical energy for propelling said motor; means for varying the direction of flow of the current therethrough so as to rotate the armature in opposite directions; locking means for locking the signal in either of two positions against the action of gravity; circuit interrupting means for simultaneously interrupting the current flow from the source of electrical energy through the motor; together with a source of electrical energy wholly independent of or disconnected from the first-named source of electrical energy for controlling the operation of the locking and current interrupting means, substantially as described.

7. A railway signal operatively connected with an electromotive device adapted to move it in opposite directions; in combination with a source of electrical energy for effecting the operation of said electromotive device; together with locking means for locking the signal in either of two positions and circuit interrupting means for interrupting the circuit to the electromotive device, said locking means and circuit interrupting means being controlled in their operation by a source of electrical energy wholly independent of or disconnected from the first-named source of electrical energy, substantially as described.

8. A railway signal operatively connected to the rotary armature of an electric motor and adapted, when released, to hang by its own weight in a vertical position; in combination with a source of electrical energy for rotating said armature; together with means for causing the armature to rotate in opposite directions, and additional means for automatically interrupting the circuit if the signal be moved beyond a definite point in either direction, substantially as described.

9. A railway signal operatively connected to the rotary armature of an electric motor; in combination with a source of electrical energy for rotating said armature, and means for causing it to rotate in either direction; together with means for locking the signal in a definite position in either of two positions against the force of gravity; a source of electrical energy wholly independent of or disconnected from the first-named source of electrical energy for controlling said locking means, and additional means for automatically interrupting the circuit of the first-named source of electrical energy if the signal be moved beyond a definite point in either direction, substantially as described.

10. In a railway system a main track, a side track and switch rails operatively connected to a switch for moving

- the switch rails in alignment with either the main or the side track rails; in combination with a signal operatively connected with the rotary armature of an electric motor; together with a source of electrical energy for said electric motor and means operatively connected with the switch for causing the armature of the motor to rotate in opposite directions when the switch is placed so that the rails are first in alignment with the main track and then in alignment with those of the side track, substantially as described. 85
11. In a railway system a switch signal operatively connected with the rotary armature of an electric motor; a source of electrical energy connected with said motor; a rail switch operatively connected with a pair of switch rails, and means connected with the rail switch for causing the armature of the motor to rotate in reverse directions dependent upon the position of the switch, substantially as described. 90
12. In a railway system a switch signal operatively connected with the rotary armature of an electric motor; a source of electrical energy connected with said motor; a rail switch operatively connected with a pair of switch rails, and means connected with the rail switch for causing the armature of the motor to rotate in reverse direction, dependent upon the position of the switch; in combination with means controlled by a source of electrical energy wholly independent of or disconnected from the first-named source of electrical energy for locking the signal in either of two positions, and additional means for simultaneously interrupting the circuit of the first-named source of electrical energy, substantially as described. 95
13. A railway signal operatively connected to the rotary armature of an electric motor; in combination with a source of electrical energy and a rail switch connected to a pair of switch rails; together with a pole changing device operatively connected to the rail switch and circuits and circuit connections whereby the signal is caused to rotate in opposite directions, dependent upon the position of the switch rails, substantially as described. 100
14. A railway signal operatively connected with the rotary armature of an electric motor; a source of electrical energy operatively connected with said motor; a pole changing device and circuits and circuit connections whereby the direction of rotation of the armature may be effected; in combination with locking means for locking the signal against the force of gravity in either of two positions; together with means for automatically interrupting the circuit of the source of electrical energy when the signal is locked, substantially as described. 105
15. In a railway system a pair of switch-rails operatively connected with a means for moving them into alignment with different pairs of rails; in combination with an electrically controlled stop-device operatively connected through circuits and circuit connections with said means; a train controlling device carried by a car or train, said stop-device being normally held out of the path of the train controlling device; together with circuits and circuit connections whereby when the switch-rails are moved out of alignment with either pair of rails the stop-device is made operative upon the train controlling device, substantially as described. 110
16. In a railway system a signal operatively connected with the rotary armature of an electric motor and adapted to assume either of three positions; in combination with a stop device movable with the signal and a train controlling device carried by a car or train, the arrangement being such that when the signal is in one of the three positions it is safe for the train to proceed, and when in either of the other two positions the train will be automatically stopped by the train controlling device, substantially as described. 115
17. In a railway system a rotary semaphore; in combination with a stop arm or device connected thereto, and a train controlling device carried by a car or train adapted to be acted upon by either the semaphore itself or the stop-arm, dependent upon the position of the semaphore, substantially as described. 120
18. A railway signal embracing a semaphore, a stop arm carried thereby and three lenses adapted to pass before a single lamp; in combination with a train stop- 125
- ping device carried by a car or train and adapted to be acted upon either by the semaphore or the stop arm, the arrangement being such that the semaphore and the lenses will give an indication of any one of three conditions, substantially as described. 130
19. In a railway system a semaphore signal operatively connected with the rotary armature of an electric motor; a pair of switch rails operatively connected with a rail switch; a source of electrical energy for propelling the motor, and means connected with the switch for causing the motor to rotate in reverse directions; in combination with a train stopping device carried by a car or train and adapted to stop the train when the semaphore indicates danger, substantially as described. 135
20. In a railway system a semaphore operatively connected with the rotary armature of an electric motor; a source of electrical energy for propelling said motor; a rail switch operatively connected with a pair of switch rails and with circuit changing devices for effecting the rotation of the armature of the motor in reverse directions; in combination with a locking device for locking the signal in either of two positions and a train controlling device carried by a car or train, the arrangement being such that when the locking device is released the train controlling device will be actuated if a motorman or engineer fails to stop his train, substantially as described. 140
21. A switch signal capable of giving two indications of track condition and a single indication of danger, said signal being controlled by an electromotive device operatively connected to a source of electrical energy and the switch lever in such manner that said lever must be left in closed position when thrown in either direction, in order to give a correct indication of the location of the switch rails by the signal, substantially as described. 145
22. A switch signal capable of giving two indications of a rail position; in combination with an electromotive device and a source of electrical energy operatively connected thereto and to the switch lever in such manner that any substantial movement of the switch rails in either direction causes the signal to give an indication of danger, unless said rails be moved through their complete phases, substantially as described. 150
23. A switch signal capable of giving two indications of rail position and a single indication of danger, said signal being operatively connected to a source of electrical energy and an electromotive device adapted to move it in opposite directions through the agency of circuits and circuit connections between the source of electrical energy, the switch, and the electromotive device; in combination with a train controlling device carried by a car or train and adapted to be actuated in such manner as to stop the train when the signal indicates danger, substantially as described. 155
24. A safety appliance for railways embracing a double or duplex stop device normally held out of action with a train control device carried by a car or train, one part of said stop device being adapted to actuate the train control device on failure or interruption of its controlling source of energy and the other for an abnormal track condition, substantially as described. 160
25. A safety appliance for railways embracing a double or duplex stop device normally held out of action with a train control device carried by a car or train, said stop device being operatively connected with a rail-switch and the arrangement such that when the switch-rails are in alignment with the main track a car or train may pass without effecting the operation of the train control device, and when the switch-rails are in reverse position or in alignment with the side track one part of the stop device will effect the stoppage of the train, and when the controlling source of energy is interrupted the other part thereof will effect the stoppage of the train, substantially as described. 165
26. A safety appliance for railways embracing a double or duplex stop device normally held out of action with a train control device, carried by a car or train, by a locking electromagnet and adapted, when released, to drop by force of gravity; in combination with an electro-motive device for moving said stop device into a different position 170

on that the second part of the stop device is placed in the path of the train control device, the arrangement being such that if the current flow through the locking magnet be interrupted it will set the stop device for action, substantially as described.

27. A railway signal of the semaphore type operatively connected with an electric motor adapted to rotate it in opposite directions; in combination with a pole changing device for varying the current relations through the motor; means for holding the signal in either of two positions and a circuit interrupting device for interrupting the circuit of the motor when thus held, the arrangement being such that the semaphore is moved in one direction to give a definite indication and in a reverse direction to give a second definite indication, and is allowed to assume a third indication through the action of gravity, substantially as described.

28. A railway signal of the semaphore type operatively connected with an electric motor; in combination with 20 a source of electrical energy for driving said motor and a pole changing device for varying the current direction through the motor; together with electromagnetically controlled locking means so constructed that when the semaphore points in either of two directions the motor is cut out of circuit and when the locking mechanism is released the semaphore hangs in a vertical position by its own weight, substantially as described.

29. A three position signal embracing a semaphore operatively connected to an electric motor; in combination with a pole-changing device adapted to reverse the direction of current through the motor; holding means for holding the signal in either of two positions, and circuit interrupting means for interrupting the motor circuit when thus held, the arrangement being such that the controlling motor is disconnected from the circuit when the signal is thus held and a third indication is given by the

signal wheel released through the influence of the force of gravity, substantially as described.

30. A three-position signal controlled by an electric motor and a pole changing device; in combination with a 40 stop-device operatively connected with the signal, substantially as described.

31. A three-position signal operatively connected with an electric motor; a pole changing device and a source of electrical energy; in combination with a stop-device controlled by the signal, and locking means independently controlled for holding the signal in either of two positions against the force of gravity, substantially as described.

32. In a railway system a main track, a side track, and a switch for effecting the conveyance of cars from one to the other; an electrically controlled stop-device normally held out of action by a closed circuit; circuits and circuit connections between the switch and the stop-device whereby the latter is made operative on the interruption of the circuit, substantially as described.

33. In a railway system a main track, a side track, and a switch for effecting the conveyance of cars from one to the other; an electrically controlled stop-device included in a normally closed circuit operatively connected with the switch in such manner that when the switch-rails are moved out of alignment with the main track the stop-device is made operative; in combination with a train control device carried by a car or train and made operative by the stop-device when the controlling circuit thereof is interrupted, substantially as described.

In testimony whereof I have signed my name to this specification in the presence of two subscribing witnesses.

CHARLES J. FINTNER.
